COMBINED REFLECTOR AND GRILLE FOR AUTOMOBILES

Donald T. French, 14323 Stahelin, Detroit, Mich.

Filed June 28, 1965, Ser. No. 85,918

Term of patent 7 years

(Cl. D14—18)

FIG. 1

FIG. 3

FIG. 1 is a rear perspective view of an automobile with the combined reflector and grille embodying my invention.

FIG. 2 is a sectional view on an enlarged scale taken along the line 2—2 in FIG. 1.

FIG. 3 is a fragmentary elevational view taken from the left in FIG. 2.

The automobile shown in broken lines is included for illustrative purposes only.

I claim:

The ornamental design for a combined reflector and grille for automobiles, as shown and described.
